UNITED STATES PATENT OFFICE.

JOHN N. JACOBSON, OF MANSFIELD CENTER, CONNECTICUT.

CHICKEN-BROODER.

SPECIFICATION forming part of Letters Patent No. 787,671, dated April 18, 1905.

Application filed April 21, 1904. Serial No. 204,232.

To all whom it may concern:

Be it known that I, JOHN N. JACOBSON, a citizen of the United States, residing at Mansfield Center, in the county of Tolland and State of Connecticut, have invented certain new and useful Improvements in Chicken-Brooders; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in chicken-brooders; and the object of the invention is to produce an apparatus of this character in which means is provided for supplying fresh air to the interior of the casing and in the causing of a circulation of heated air to pass from the heating-chamber at the top of the brooder down through the interior thereof and through a space between the double flooring and double siding of the brooder, thereby utilizing to the fullest extent the heat.

The invention consists, further, in various details of construction and combinations and arrangements of parts, which will be herein-after fully described and then specifically defined in the appended claims.

My invention is illustrated in the accompanying drawings, which, with the letters of reference marked thereon, form a part of this application, and in which drawings similar letters of reference indicate like parts in the views, in which—

Figure 1 is a vertical sectional view through my improved brooder, showing parts in elevation. Fig. 2 is a longitudinal sectional view through the brooder on line 2 2 of Fig. 1. Fig. 3 is a sectional view on line 3 3 of Fig. 1. Fig. 4 is a sectional view transversely through the brooder, showing the partitions with a hinged door in elevation.

Reference now being had to the details of the drawings by letter, A designates the casing of the brooder, which may be of any size and shape, and B is a partition dividing the casing into two compartments, one of which

contains a heating-chamber C, which is fastened to the cover D, which is hinged to the casing, and said compartment containing the heating-chamber has double floors, (indicated in the sectional view by letters E and E') with a space intervening between the same, and on the inner face of the front wall of the casing is a flue or passage-way E², communicating with a space between the two floorings, and inlet-apertures e afford means of communication between the compartment containing the heating-chamber and said flue. Suitable screens e' are placed over said openings or apertures to prevent chickens or foreign matter entering said flue. One side of the casing has a double wall, said walls being indicated in the drawings by letters G and G' and spaced apart, said space communicating with the space intermediate the double flooring and leading up to the upper edge of the casing, where the space is closed and provided with exit-apertures N, which are adapted to receive pipes K', passing through apertures in the cover, and which pipes when the cover is closed communicate with the space intermediate the double sidings. When said cover D is closed, a continuous passage-way will be afforded through the apertures N and K and pipes K' and through which the vitiated air coming from the interior of the compartment may escape to the atmosphere.

Upon the front side of the brooder-casing is a boxing Q, in which a lamp Q' of any suitable kind affording means of supplying heat is positioned, and a door Q² is hinged to said boxing and provided with a window g, whereby access may be had to the interior of the boxing or sight of the same had through the window. A series of apertures O' are made through the lower end of the side of said boxing for the purpose of supplying fresh air to the interior of the casing for combustion purposes and for ventilating the interior of the brooder. A window a is provided in the front wall of the casing, and a thermometer A² is positioned inside of the casing adjacent to the window a, whereby the temperature of the brooding-chamber may be determined from the outside.

The front wall of the casing has a recessed

portion a' , adapted to receive the contracted end C^2 of the heating-chamber, and depending from said contracted end of the heating-chamber is a cylindrical passage-way C^3 , which when the cover D is closed is adapted to telescope over the end of a chimney of a lamp positioned in said boxing. Said heating-compartment has a transverse partition C^4 dividing it into two compartments. The upper compartment (designated by letter O) is adapted to receive fresh air through the apertures O' , which are positioned in the lower part of the boxing containing the lamp, and the fresh air passes through said space and makes exit at the point indicated by the arrow J near the upper end of the compartment and adjacent to the rear wall thereof, the course of the fresh air being indicated by the arrows as it issues in the upper rear end of the compartment and passes down near the bottom of the compartment and makes exit through the apertures e and continuing its course, as indicated by arrows, between the two floorings and the double siding preparatory to its making exit through the pipes which communicate with the space between the rear walls of the casing.

The heating-compartment C only is provided with series of transverse partitions, having their alternate ends free, whereby the heat which enters the heating-chamber from the lamp is caused to travel back and forth repeatedly until it finally escapes through the chimney R to the atmosphere. Hinged upon the partition B is a door I , adapted to partially close the opening between the two compartments in the brooder, and fastened to the lower free edge of said door is a fabric I' , by which the chickens are allowed to freely pass. This hinged door is provided for the purpose of allowing the smaller chickens to pass into the compartment containing the heating-chamber, and when it is desired to adapt the brooder for use with larger chickens said door may be swung open to allow the chickens to pass freely from the compartment containing the heating-chamber into the second chamber at will. Said second chamber is provided with a window upon one side and slide-covered apertures, whereby the contents of the compartment may be seen from the outside, and a sliding door T is provided, through which the chickens are allowed to pass. A cover S is hinged to the compartment containing said sliding door, whereby ready access may be had to the contents of the brooder.

From the foregoing description, when taken in connection with the drawings which form a part of this application, it will be observed that an efficient means for thoroughly ventilating the brooder is provided, in which the fresh air is drawn into the heating-chamber and caused to circulate back and forth through the circuitous course in the

heating-chamber, thereby utilizing the heat to its fullest extent before it escapes to the atmosphere, and in the provision of means for drawing the fresh air through a compartment of the heating-chamber and making exit near the top of the brooding-compartment and thence passing down through and making exit through the space between the double flooring and double siding, thus serving to keep the bottom and side of the compartment from cooling, and by the provision of the hinged door in the partition between the two compartments of the casing means is provided for the ready passage of the larger chickens by fastening the door open.

While I have shown a particular detailed construction of chicken-brooders embodying the features of my invention, it will be understood that I may make alterations, if desired, in the detailed construction of the apparatus without in any way departing from the spirit of the invention.

Having thus fully described my invention, what I claim as new, and desire to secure by Letters Patent, is—

1. A chicken-brooder comprising a casing having a double bottom and a double end, a hinged cover to said casing, a fresh-air-heating chamber fastened to said cover, a compartment heating-chamber attached to and beneath said fresh-air-heating chamber, a brooding - compartment underneath said chambers, a heater communicating with said compartment heating-chamber, said fresh-air-heating chamber communicating with the interior of said casing, and the latter communicating with the atmosphere through a passage-way leading from the brooding-compartment through the double bottom and end of the casing, as set forth.

2. A chicken-brooder comprising a casing having a double bottom and a double end, a brooding-chamber, a hinged cover to said casing, a fresh-air-heating chamber secured to said cover, a heater communicating with said fresh-air-heating chamber, a compartment heating-chamber, partitions therein fastened to and beneath said heating-chamber, said compartment heating-chamber having a passage - way leading about alternate ends of said partitions, pipes carried by said cover, said fresh-air-heating chamber communicating with the interior of said brooding-chamber, and the latter communicating with the atmosphere through a passage-way leading between the double flooring and double end, and said pipes, as set forth.

3. A brooder comprising a casing having a double bottom and one double end with spaces intervening between said double bottom and double end, a hinged cover to the casing, pipes carried by said cover, a fresh-air-heating chamber secured to the cover, a compartment heating-chamber secured to the bottom of said fresh-air-heating cham-

ber, a brooding - compartment below said chambers, a heater adapted to communicate with said compartment heating - chamber, said fresh-air-heating chamber opening into 5 said brooding - compartment near the top and rear wall of the latter, said brooding-chamber communicating with the atmosphere through the space intervening between said double bottom and double end 10 wall, and said pipes, as set forth.

4. A chicken-brooder comprising a casing, a hinged cover mounted thereon, a two-compartment heating-chamber carried by said cover, one of said compartments having a series of partitions so arranged as to form a circuitous course for the passage of heat, a lamp-containing compartment having communication with said partitions-heating compartment, a double bottom and a double side to 15 the brooder, with spaces intervening between the bottom and double side, which spaces form a passage-way, pipes carried by the hinged cover and adapted, when the cover is closed, to communicate with said passage- 20 way, as set forth.

5. A brooder comprising a casing with hinged cover, a brooding - chamber within said casing, a heating-chamber having a contracted end carried by said cover and divided 30 into two compartments, one for the passage of the products of combustion through a circuitous passage-way, the other for the admission of fresh air and adapted to open into the brooder-chamber, a lamp-containing box, 35 said heating-chamber having a passage-way leading from its contracted end and adapted to fit over the chimney of a lamp within said box, a downwardly-projecting portion of said heating-chamber affording an inlet-passage 40 for fresh air, said contracted portion of the heating-chamber adapted to enter a cut-away portion of the casing as the cover is closed, a

double flooring and double end walls with space intervening between the two floors and double end walls, a flue communicating with the space between the double flooring and having openings leading therefrom into the brooding-chamber near the bottom thereof, an apertured strip closing the space between the double end walls of the casing, pipes passing through apertures in the cover and adapted to register with the apertures in said strip when the cover is closed, as set forth. 45

6. A brooder comprising a casing divided into two compartments, a cover hinged to 50 said casing, a partition between said compartments, a door hinged to said partition, a fabric secured to the edge of said door, a fresh-air-heating chamber secured to said cover and having a contracted portion, a compartment heating-chamber underneath and secured to said fresh-air-heating chamber, said casing having a double bottom and a double end, with communicating spaces between the double bottom and the double end, which 55 spaces communicate with the interior brooding-chamber near the bottom thereof, a lamp and box therefor into which the contracted portion of the compartment heating-chamber is adapted to be positioned when the cover 60 is closed, and a duct opening into the compartment-chamber and adapted to telescope over the chimney of the lamp in said box, said fresh-air-heating chamber having a passage-way for the admission of fresh air, and a 65 communicating passage-way between the fresh-air-heating chamber and the brooding-compartment, as set forth.

In testimony whereof I hereunto affix my signature in presence of two witnesses.

JOHN N. JACOBSON.
